UNITED STATES PATENT OFFICE.

JOHN McLEOD, OF CARBERRY, MANITOBA, CANADA, ASSIGNOR TO BENJAMIN STEWART, OF CARBERRY, CANADA.

SHOCKING-MACHINE.

995,885.

Specification of Letters Patent. Patented June 20, 1911.

Application filed April 16, 1909. Serial No. 490,347.

To all whom it may concern:

Be it known that I, JOHN McLEOD, of the town of Carberry, in the Province of Manitoba, Canada, have invented certain new and 5 useful Improvements in Shocking-Machines, of which the following is the specification.

My invention relates to shocking machines and the object of the invention is to provide a machine which can be attached to the 10 usual binding machine and be operated thereby and which will receive the sheaves thrown from the binder delivery tray, collect them, and deposit them butts down in a shock on the field, the machine being fully 15 under the control of a single operator.

My invention further specifically resides in the following features of construction, arrangement, and operation, as will herein-after be set forth, reference being made to 20 the accompanying drawings in which—

Figure 1 is a side elevation of the complete machine as it appears when attached to the binding machine and in a position to receive the sheaves therefrom. Fig. 2 represents a plan view as in Fig. 1, the parts of 25 the binder appearing in Fig. 1 being removed, as also are certain parts adjoining the binder tray. Fig. 3 is a plan view showing the parts as they appear when a shock 30 is being deposited on the ground. Fig. 4 represents a vertical cross sectional view through the machine in the plane denoted by the line X X¹, Fig. 1, and looking in the direction of the arrow, certain parts being omitted for the sake of clearness. Fig. 35 5 is a vertical cross sectional view in the plane denoted by the line X X¹, Fig. 1, and looking in the opposite direction to that of Fig. 4. Fig. 6 is an enlarged, detailed side 40 elevation of the head or frame carried by the casting showing the gears and clutch mechanism located therein. Fig. 7 is a side elevation of the links which carry and control the fingers. Fig. 8 is an enlarged detailed perspective view of the main casting, 45 the head pivotally secured thereto, and the attachments carried thereby. Fig. 9 is an enlarged detailed end view of the main casting or supporting frame. Fig. 10 is a vertical sectional view through the frame 35 the section being taken in the plane denoted by the line Z Z¹, Fig. 6, and looking in the

direction of the arrow. Fig. 11 is a detailed side view of the steadier bar and the supporting shafts showing them as they appear 55 when detached from the remainder of the machine.

In the drawings like characters of reference indicate corresponding parts in each figure.

1 represents the main or bull wheel of a binder and 2 the binder frame.

3 is a cross beam carried by the frame on which is secured the usual seat 4. To the cross member 2¹ of the frame I attach my 65 machine in a manner shortly to be described.

5 represents the tongue of the binding machine.

6 represents the main beam of my shocking machine from which extends rearwardly 70 and backwardly at one end a transverse beam 7, said beams being fastened the one to the other in any desired manner.

7¹ is a caster wheel pivotally secured by a pin 7² to the free end of the beam 7, it 75 being noticed that the beam inclines slightly upwardly in passing from the beam 6 to the caster wheel.

8 is a carriage wheel mounted in a stub shaft 8¹ extending from a casting 8² which 80 is firmly bolted at 8³ to the main beam. The caster wheel and the wheel 8 are normally in parallel planes.

9 is the main casting which is composed of a vertically extending member 9¹ having 85 two extending and parallel arms 9² and 9³, and has an off set portion 10 which is provided at its extending end with laterally projecting portions 10¹ suitably reinforced and adapted to receive and be secured to the 90 end of the main beam 6. The portion 10 carries an extending axle 11 upon which is mounted the drive or traction wheel 11¹. In this way the shocking machine is carried by three wheels, two at the front, and one at the 95 rear. Centrally of the beam 6 is secured the tongue 12 of the shocking machine suitably reinforced by braces 12¹ which pass between the tongue and the beam.

13 is a cross bar connecting the tongue 5 100 and the tongue 12. By attaching the draft animals to the bar 13 in any convenient way it is possible to draw the binder and the shocking machine together.

14 is a bar passing from the beam 7 to the cross member 2¹ of the binder frame, thereby uniting such portions firmly together.

15 represents the sheaf delivery tray 5 which is carried by the binder and overhangs the bull wheel 1.

In the binding machine the sheaves are passed over the tray and delivered therefrom, delivery being controlled by an automatic device which allows them to pass from the tray one after another in succession. This device or mechanism is shown at 15¹, but the operation of the parts is not explained, as this forms no part of my invention.

16 16¹ are vertically directed posts secured firmly at their lower ends to the beam 7 by suitable bolts 16². The posts 16, 16¹ are united by a cross bar 16³.

20 17 17¹ are brackets secured firmly to the posts 16 16¹, respectively, and directly opposite each other in a horizontal plane. The brackets are located almost immediately opposite the lower end of the delivery tray 15, 25 the reason for this being shortly apparent.

18 is a sheaf receiving table pivotally suspended at one side by a cross shaft 18¹ which is carried in suitable bearings formed in the brackets 17 and 17¹, respectively. The 30 shaft is provided with a crank end 18² which is united through the link 18³ with the bell crank 19, pivotally secured at its angle by a pin 19¹ to the beam 3 of the binding machine. The bell crank is connected through

35 a rod 19² with the double crank foot lever 19³ carried on the beam 3 and within convenient range of the seat 4. The link 19² is forced in one direction by pressing on the foot rest 19⁴, and in the opposite direction 40 by pressing on the foot rest 19⁵, as will readily be understood.

20 are spiral springs secured at their upper ends to the posts 16 and 16¹, respectively, and at their lower ends to the sides of the 45 platform, in this way supporting the platform.

21 21¹ are bars passing vertically upwardly from the sides of the platform 18 to which they are pivotally secured by suitable bolts 50 21², the bars being united at their upper ends by a cross bar 21.

22 22¹ are horizontal bars pivotally secured at their ends to the bars 21 21¹ and the posts 16 16¹, respectively.

55 23 is a stub shaft carried by the post 16 toward its upper end and upon the shaft are mounted two chain gears 23¹ 23², it being understood that the chain gears are keyed on the shaft, and the shaft is free to rotate 60 in suitable bearings formed in the post.

24 is a crank shaft mounted in suitable bearings 24¹ carried by the bars 21 21¹. The shaft is provided with three cranks 24² and has a chain wheel 24³ keyed on one end, said 65 chain wheel being connected through the

agency of a chain 24⁴ with the chain wheel 23².

25 are beams extending downwardly from the cross bar 21³ to which they are firmly secured there being four such beams spaced 70 at equal distances along the bar. Each beam carries a bearing 25¹ for the shaft 24, the bearing appearing at each side of the cranks 24².

25² are shields secured at their upper ends 75 firmly to the cross bar 21³ and at their lower ends to the cross members 25³ appearing at the lower ends of the beams 25. The shields are bulged or bent considerably and serve to collect the sheaves coming from the delivery 80 tray, at the same time protecting the crank shaft and the parts secured thereto.

26 are bars secured by straps 26¹ to the cranks 24² and being slidably received at their upper ends by straps 26² carried by the cross bar 21³. The bars are in this way free to take the motion required by the crank shaft in its rotation. It will be noticed that the bars pass between the adjoining edges of the shields and extend downwardly normally above the platform. The platform is slotted at 27 to allow the points of the bars to pass below the platform in their movement as occasioned by the throw of the cranks. 90

28 28¹ are sets of flaps those 28 being hinged to the edge of the platform and those 28¹ to the lower end of the shields. The flaps of each set overlap each other and are held in a substantially vertical position by 100 spiral springs 28² which allow them to be passed to the horizontal position.

29 is a plate secured firmly to the upper face of the beam 6, said plate being provided with journals 29¹ and 29² set at right 105 angles to each other, as best shown in Figs. 2 and 3.

30 is a short shaft mounted in the journal 29¹ and having at its one end a chain wheel 30¹ and at its other end a bevel pinion 30². 110 The chain wheel 30¹ is connected to the chain, wheel 28¹ by the chain 30³ so that the motion of the crank shaft is directly controlled by the shaft 30.

31 is a journal formed on the arm 9² of 115 the casting 9 and 31¹ is a shaft rotatably mounted in the journal and having a bevel pinion 31² secured to its one end and a chain wheel 31³ secured to its other end.

32 is a journal bolted firmly to the member 10¹ and to the upper side, and 32¹ is a shaft mounted in the journals 32 and 29², respectively, said shaft being provided at its one end with a bevel pinion 32². 120

33 is an idler wheel centered on a pin 33¹ 125 carried by the portion 10.

33² is a chain wheel on the shaft 11 and rotatable with the traction wheel 11¹. The chain wheels 31³ and 33², and the idler 33 are all in the same plane.

34 is a chain wheel keyed on the end of the shaft 32¹ and in the same plane as the adjoining chain wheels, and 34¹ is a continuous chain passing over the chain wheel 31³ under 5 the chain wheel 33² over the idler wheel 33 and under and around the chain wheel 34, in this way transmitting the motion of the traction wheel to the various chain wheels.

35 is a metallic supporting frame formed 10 from a continuous band having two transversely extending and two vertically extending portions 35⁴ and 35², respectively. The frame 35 is pivotally secured to the arms 9² and 9³ of the casting 9 in the following manner,--A pivot pin 35³ passes from the center 15 of the arm 9³ upwardly and into an opening 35⁴ formed in the lower member 35¹ of the frame. A spacing member 36 is introduced between the arm 9² and the upper cross member 35¹ of the frame and a pin 36¹ passes 20 downwardly through the arm, the member 36, and frame 35, such pin being rotatable within a bushing 36² passing through the aforesaid members. Bevel pinions 37 and 25 37¹ are secured firmly to the ends of the pin 36¹ so that it is prevented from longitudinal displacement within the bushing. The bevel pinion 37 is located within the frame 35, and the bevel pinion 37¹ without, being 30 directly above the arm 9². The bevel pinion 31² and the bevel pinion 37¹ are located so that they are in mesh.

38 is a cross shaft mounted in suitable bearings 38¹ formed centrally in the vertically extending side pieces 35² of the frame.

39 and 39¹ are bevel pinions rotatable on the shaft 38 and located directly opposite each other, being positioned so that they 40 mesh with the bevel pinion 37 hereinbefore referred to. The shaft 38 passes at right angles to the pin 36¹.

The bevel pinions 39 and 39¹ are provided with shoulders 39² which bear against the 45 inner faces of the upright portions 35², and accordingly the bevel pinions are prevented from longitudinal displacement on the shaft. The opposing faces of the bevel pinions 39 and 39¹ are supplied with drive members 40 and 40¹ of a clutch, and upon the shaft 38 are located driven members 40² 40³, which are held in slidable relation to the shaft by feathers 40⁴. The driven members of the clutches have each an extending portion 41 in which is formed a groove or channel 41¹, the purpose of which will hereinafter be explained.

42 is an extending shaft firmly fastened to the shaft 38 by means of the coupling 42¹. 60 It will be noticed that the shaft 42 passes at right angles from the shaft 38 so that when the shaft 38 rotates the attached shaft is free to swing forwardly and backwardly. Centrally of the length of the shaft 42 I 65 have secured a vertically directed standard

43, such being firmly held to the shaft in any convenient manner.

44 is a bar or rod secured firmly to the upper end of the standard 43 and passing at right angles therefrom, such rod in a 70 certain position of that portion being substantially horizontal or parallel with the ground, as is best shown in Fig. 4. Toward the ends of the shaft 42 and at equal distances from the standard 43 are placed complementary bars 45 45¹, such bars being pivotally secured to the shaft 42 by means of any suitable form of pivot bolt. The bars have one portion 45² thereof bent at right angles to the body portion, the purpose 75 of which will be later explained.

46 is a rocker arm pivoted centrally to the upper end of the standard 43, and 47 and 47¹ are links connecting the rocker arm with the bars 45 and 45¹, respectively. The extending end 46¹ of the rocker arm is connected through the link 48 with the casting 49 which is secured to the upright member 35² of the supporting frame 35 which is supplied with extending lugs 49¹ to which 90 the link is pinned. The casting 49 is firmly bolted to the frame 35 and is provided with an extending member 49² which forms at 49³ a rest for the shaft 42 in a certain position of the shaft.

50 and 50¹ are sets of arms each secured at one end firmly to the bars 45 and 45¹ said bars carrying in their other ends shafts 50² 50³ which unite the bars and are rotatable in the upper ends thereof.

51 51¹ are sets of curved forearms or fingers secured firmly to the shaft and rotatable therewith. The free end of the forearms are turned or hooked backwardly at 51² so as to present a blunt end to the arms.

52 52¹ are rods extending at right angles from the ends of the turned portions 45² of the bars 45 45¹ respectively.

53 is a shaft adjoining the shaft 42 and running parallel therewith, said shaft 53 being rotatably mounted in bearings formed in brackets 53¹ extending from the shaft 42.

53² are arms secured to the ends of the shaft 53 and connected through the links 53⁴ to the cranks 54 formed at the ends of the shafts 50² and 50³, respectively. Holes are provided in the cranks 54 for adjustment purposes.

55 55¹ are bars each firmly secured at one end to the shaft 53 and said bars being united at their other ends through a ring or short cylinder 55² to which they are both pivotally secured.

56 is a bar which I have termed the steadier bar and it is fastened to the bars 55 55¹ by means of rods 57 57¹ which are pivotally secured to both the steadier bar and the bars 55 55¹. The upper end of the steadier bar passes slidably into the ring 55².

The bar 44 carried at the end of the stand-

ard 43 passes between a set of opposing pulleys 58 which are carried by the bar 56.

59 and 59¹ are two arched strips secured firmly to the steadier bar centrally of their 5 length and appearing one directly above the other. The strips are horizontal when the point of the steadier bar is in the ground.

60 is a bar pivotally secured at 60¹ to the upper face of the main beam 6 and 60² 10 is a link secured pivotally at one end to the bar and at the other end to the lugs 60³ supplied on the frame 35.

61 is a rod pivotally secured to the bar 60 and to the bell crank 61², said bell crank 15 being pivotally connected to the beam 3. 61³ is a lever supplied with the ordinary hand latch 61⁴ and detent 61⁵ operating over the quadrant 61² carried by the beam 3.

63 is a rod secured to the lever and to 20 the free arm of the bell crank 61².

64 and 64¹ (Fig. 6) are spring bars having their lower ends firmly bolted at 64² to the lower cross member 35¹ of the frame 35 and having their upper ends bifurcated 25 and entering the channels 41¹ formed in the portions 41 of the clutches.

65 is an operating bar having its one end passing through a suitable opening 65¹ formed in one of the upright portions 35² 30 of the frame 35, and its other end 65² received within a rectangular opening 65³ located in the spring bar 64. A shoulder 65⁴ is formed on the bar slightly in from the end 65² and the rectangular opening is designed to receive the bar and shoulder slidably.

66 is an arched flat spring secured at 66¹ by a pin to the bar 65 and by rivets 66² to the lower member 35¹ of the frame 35. The 40 object of the spring is to press the bar upwardly against the top of the opening 65¹ and at the same time backwardly from the opening.

67 is a plate pivotally connected to the 45 upright portion 35² of the frame 35, such plate resting normally against the end of the bar 65 which extends through the opening 65¹.

68 is a bar centered on a pin 68¹ which 50 passes through the strap 68² and into the frame 35.

69 is an operating bar bolted at 69¹ to the upper end of the bar 68 and having its free end passing through a rectangular opening 55 at 69² in the spring bar 64¹, similar to that at 65³. A shoulder 69³ is formed on the bar slightly back from the extending end.

70 is an arched flat spring fastened at 70¹ to the bar 69 and at 70² to the portion 35¹ 60 of the frame 35. The tendency of the spring is to withdraw the bar from the opening and at the same time press it upwardly.

71 and 71¹ are lugs extending from the peripheral faces of the female members 40² 65 40³ of the clutches, such lugs being designed

to engage with the adjoining end of the bars 65 and 69, respectively.

72 is an arm firmly secured to the shaft 53 and designed in a certain predetermined position of the shaft to engage with and depress the plate 67 thereby actuating the bar 65.

The frame 35 has a projecting portion 35^x passing from the upper cross portion 35¹ thereof and to this portion is secured a plate 75 73 having lugs 73¹ formed thereon which carry a pin 73² on which is pivoted a latch 74 having a notch 74¹ on its lower edge.

75 is a flat spring having its one end arched and fastened or tied to the upper 80 side of the latch and passing over the upper face of the portion 35^x, the opposite end of the spring being bent and fastened at 76 to the under face of such portion.

77 is an arm secured to the shaft 53 and 85 designed in a certain position of the shaft, as will hereinafter become more apparent, to engage with the upwardly directed lug 49⁴ formed on the casting 49, and also with the extending end of the latch 74, it being 90 noticed that the latch extends to the side of the lug 49⁴.

In order to better understand the shocking machine I will now describe its operation, it being assumed that the parts are in a position as shown in Fig. 1, further assuming 95 that the machine is progressing and that sheaves are being delivered from the binder tray 15 to the platform 18.

The forward motion of the machine causes the shafts 31¹ and 32¹ to rotate by virtue of the chain 34¹. The shaft 32¹ controls the operation of the crank shaft 24 which in its rotation moves the bars 26, they having a forward and backward as well as an upward and downward motion. The sheaves thrown on the platform are carried by the bars 26 forwardly on the platform and pressed through the flaps 28 and 28¹ which return to their normal position as soon as the sheaf is passed from the platform. The operator at this time presses the foot lever 19³ so as to bring the platform in a direct line with the ends of the set of forearms or fingers 51¹. The sheaves are consequently passed from the platform through the flaps to the fingers 51¹ and below the bar 44, the butts of the sheaves resting against the rods 52 52¹. As soon as the space between the set of fingers 51¹ and the bar 44 is filled 120 the platform is raised by operating the foot lever 19³ to a position which will place it directly in a line with the bar 44 so that any further sheaves delivered pass to the upper side of the bar and between the bar and the set of fingers 51.

The arched strips 59¹ form a back against which the sheaves are forced and together with the arms form the sheaves into a shock. When the formation of the shock 130

is completed, that is, when the space between the sets of fingers and the strips is completely filled with sheaves, the operator pulls backwardly on the lever 61³ which through the bell crank and links swings the frame 35 a quarter turn, in this way swinging the shock away from the platform. The frame 35 then assumes the position shown in Fig. 3, and is locked in this position by the notch in the latch 74 passing over the arm 9² (Fig. 8). As the frame 35 swings the quarter turn above mentioned the body of the spring 75 is depressed between the under face of the arm 9² and the upper face of the portion 35¹, and this causes the free end of the spring to force the latch downwardly against the arm 9², so that it is in this way automatically locked. As the frame 35 is being turned the quarter turn the bar 68 is brought into contact with the edge of the arm 9². The bar swings on its pivotal point and forces the actuating bar 69 lengthwise. The shoulder 69³ of the bar is at this time engaging with the inner face of the spring bar 64¹ so that the spring bar is carried with the actuating bar and, as its forked end is connected with the driven member 40³ of the clutch, it throws the members of the clutch into engagement.

The bevel pinion 37 is continuously rotated by the bevel pinion 37¹ which is in mesh with the bevel pinion 31² on the shaft 31¹ which in turn is operated by the chain 34¹. Consequently as soon as the aforesaid members of the clutch are engaged the bevel pinion 37 which is constantly rotated by the bevel pinion 37¹ carries with it the shaft 38, and the shaft in rotating swings the shaft 42 a quarter turn, this being controlled by the lug 71¹ which at a predetermined instant engages with the extending end of the bar 69 and forces it downwardly. As soon as the bar is pressed downwardly sufficient to allow it to slide through the opening 69² the spring bar 64¹ disengages the members of the clutch and assumes the position shown in Fig. 6 thereby stopping the rotation of the shaft.

As the shaft 42 swings a quarter turn the link 48 is actuated in such a manner that the complementary bars 45 45¹ are swung to the position shown in dotted outline in Fig. 7. The sets of fingers 51 and 51¹ and also the rods 52 and 52¹ are then in the position as shown in Fig. 3, and it will be seen that the effect of this movement is to tighten the fingers on the head of the shock and spread the rods at the butt of the shock thereby putting the shock into the best condition for depositing on the ground. Immediately the shaft 42 finishes its movement the point of the steadier bar enters the ground and remains stationary, the remainder of the machine in the forward

motion of the draft animals passing on. As the draft animals advance the shaft 53 is rotated by the action of the bars 55 55¹, and the rods 57, 57¹. The rotation of the shaft gradually opens the sets of fore-arms 51 51¹ through the links 53¹ so that the shock is freed. The strips 59 and 59¹ cause the shock to pass away from the fingers and steady it until it is left standing by itself on the ground. The relative position of the 75 steadier bar to the machine at the time the shock is delivered entirely from the fingers is shown in dotted outline in Fig. 4. The same rotation of the shaft 53 as caused by the steadier bar brings the arm 72 into engagement with the plate 67 and forces the plate inwardly toward the frame 35. The plate carries with it the bar 65 and the shoulder 65⁴ on the bar engaging with the face of the spring bar forces it toward the 80 bevel pinion 39 so that the driven member 40² of the clutch is brought into engagement with the drive member 40. The shaft 38 is rotated by the bevel pinion 39 in an opposite direction to that already described 85 and the shaft 42 is swung one quarter turn in the opposite direction to that hereinbefore stated. When it has been turned one quarter turn (return motion) the lug 71 engages with the adjoining end of the 90 bar 65 and depresses it sufficiently to allow the spring bar 64 to release itself from the shoulder 65⁴ and it carries with it the driven member 40² of the clutch, and the shaft stops rotating. The arm 72 must not 95 pass off the plate 67 in turning until the shaft has reached the original or upright position for the reason that as soon as the arm passes away from the plate, the spring bar 64 will be free to spring back and disengage the clutch members. This must not take place until the shaft is practically in the upright position. Consequently, the plate 67 is provided with a side extension 100 105 110 115 120 125 130 135 140 145 150 155 160 165 170 175 180 185 190 195 200 205 210 215 220 225 230 235 240 245 250 255 260 265 270 its original position, as it will be understood the point was withdrawn from the ground as soon as the shaft 42 commenced to return. The bar 44 serves as a liner for the steadier 5 bar, as the steadier bar has to move or slide along it on account of the pulleys. At the same time that the arm 77 is engaging with the lug 49 it is being gradually slipped toward the end of the lug and accordingly it 10 engages with the latch 74 and raises it so as to free the notch from the arm 9. This is done just before the shaft 42 resumes its normal position. The operator now returns the frame 35 to its original position by 15 pressing the foot lever so as to move the rod 61 in an opposite direction to its original movement which swung the frame the first quarter turn, that is, to the position shown in Fig. 3. It would be impossible to swing 20 the frame if the latch 74 were not released as above explained.

The complete operation as hereinbefore described is repeated each time a shock is deposited on the ground.

25 What I claim as my invention is:

1. In a shocking machine, the combination with the sheaf delivery tray of a binding machine and an adjoining receiving platform carrying means for delivering sheaves 30 from the platform, of means designed to receive the sheaves to form a shock and adapted to be turned one-quarter turn in a horizontal position, and to be swung one-quarter turn in a vertical plane to deposit the shock 35 butt down on the ground, said means being further designed to tighten on the head of the sheaves and loosen the butts of the sheaves forming the shock when being turned in the vertical plane, as and for the 40 purpose specified.

2. In a shocking machine, the combination with the sheaf delivery tray of a binding machine and an adjoining receiving platform carrying means for delivering sheaves 45 from the platform, of means designed in the normal position to receive the sheaves in their horizontal position to form a shock and adapted to be swung one-quarter turn in a horizontal plane and to be turned in a vertical plane thereby depositing the shock butt 50 down on the ground, and means for steady- ing the shock after it has been deposited on the ground, as and for the purpose specified.

3. In a shocking machine, the combination 55 with the sheaf delivery tray of a binding machine and an adjoining receiving platform carrying means for delivering sheaves from the platform, of means designed to receive the sheaves to form a shock and adapt- 60 ed to be turned one-quarter turn in a horizontal position, and to be swung one-quarter turn in a vertical plane to deposit the shock butt down on the ground, said means being further designed to tighten on the head of the 65 sheaves and loosen the butts of the

sheaves forming the shock when being turned in the vertical plane, and means adapted to steady the shock after it is de- 70 posited on the ground, as and for the purpose specified.

4. In a shocking machine, the combination with the binding machine frame and sheaf delivery tray, of suitable supporting beams secured to the binding machine frame and adjoining the sheaf delivery tray thereof, of 75 an adjustable horizontally extending platform adapted to receive the sheaves from the tray; bars slidably constrained at their upper ends, a rotatably mounted crank carrying said bars, said bars being adapted to pass the sheaves from the platform; and shields interposed between the bars, as and for the purpose specified.

5. In a shocking machine, the combination with the binding machine frame and sheaf delivery tray, of suitable supporting beams secured to the binding machine frame and adjoining the sheaf delivery tray thereof, of 80 an adjustable horizontally extending platform adapted to receive the sheaves from the tray; bars slidably constrained at their upper ends, a rotatably mounted crank carrying said bars, said bars being adapted to pass the sheaves from the platform; bulged shields interposed between the respective 85 bars; and opposing sets of cooperating 90 spring pressed flaps carried the one by the platform and the other at the lower ends of the shields, as and for the purpose specified.

6. In a shocking machine, the combination with suitable supporting beams extending at right angles the one from the other, of a set of opposing vertical posts secured to one beam; brackets extending from the posts; a platform connected with said brackets; 100 springs supporting the free side of the platform; opposing horizontally extending bars pivotally secured to the upper ends of the posts; vertically directed bars secured pivotally to the platform and to the aforesaid 105 bars; a cross bar connecting the upper ends of said vertically directed bars; a crank shaft carried by the said vertical bars; bars secured to the cranks of the crank shaft and having their upper ends slidably connected with the 110 cross bar uniting the upper ends of the vertical bars; beams extending downwardly from the latter cross bar; cross members supported by the beams; shields interposed be- 115 tween the respective slidable bars and se- 120 cured at their upper ends to the said cross bar and at their lower ends to the cross members supported by the beams; opposing sets of vertically extending, coöperating spring 125 pressed flaps pivotally secured, the one set to the side of the platform and the other to the lower ends of the shields; and means for rotating the crank shaft, as and for the purpose specified.

7. In a shocking machine, the combination 130

with a binding machine and a sheaf delivery tray and a set of connected beams secured to the binding machine frame, wheels for supporting said beams a receiving platform carried by one of said beams and located adjacent the delivery tray means for delivering the sheaves from the platform, of a main stationary casting secured to the other of the beams and having two parallel arms extending therefrom; a supporting frame pivotally secured between the arms; a cross shaft mounted in suitable bearings formed in the sides of the supporting frame; means for turning the said frame an extending shaft secured to the cross shaft and passing at right angles therefrom; means for rotating the cross shaft and means carried by the extending shaft and adapted to receive the sheaves passed from the platform and form them into a shock, as and for the purpose specified.

8. In a shocking machine, the combination with a binding machine and a sheaf delivery tray and a set of connected beams secured to the frame of the binding machine supporting wheels for said beams a receiving platform carried by said beams and located adjacent the delivery tray and provided with means for delivering the sheaves from the platform, of a main stationary casting secured to one of the beams and having two parallel arms extending therefrom; a supporting frame pivotally secured between the arms means for turning the same; a cross shaft mounted in suitable bearings formed in the sides of the supporting frame; an extending shaft secured to the cross shaft and passing at right angles therefrom; means controlled by the turning of said frame for rotating the cross shaft; and means carried by the extending shaft for receiving the sheaves from the platform and designed to form them into a shock, as and for the purpose specified.

45 9. In a shocking machine, the combination with a binding machine and its sheaf delivery tray a set of connected beams secured to the binding machine frame, wheels for said beams a receiving platform carried by one of said beams and located adjacent the delivery tray and provided with means for delivering the sheaves from the platform, of a main stationary casting secured to the other of the beams and having two parallel arms extending therefrom; a supporting frame pivotally secured between the arms means for turning the same and locking it in such turned position; a cross shaft mounted in the sides of the supporting frame; an extending shaft secured to the cross shaft and passing at right angles therefrom; means controlled by the turning of said frame for rotating the cross shaft; complementary bars pivotally secured to the extending shaft; arms firmly secured to the bars; cross shafts

mounted in the free ends of the arms; fingers carried by said shafts means for swinging the complementary bars on their pivotal points at a predetermined period; and means for rotating the shafts carrying the fingers at a predetermined period, as and for the purpose specified.

10. In a shocking machine, the combination with a binding machine and its sheaf delivery tray a set of connected beams secured to the binding machine frame, wheels for said beams a receiving platform carried by one of said beams and located adjacent the delivery tray and provided with means for delivering the sheaves from the platform, of a main stationary casting secured to the other of the beams and having two parallel arms extending therefrom; a supporting frame pivotally secured between the arms; a cross shaft mounted in the sides of the supporting frame; an extending shaft secured to the cross shaft and passing at right angles therefrom; means for rotating the cross shaft; means for turning the supporting frame and for locking it in such turned position; a pair of complementary bars pivotally secured to the extending shaft and having each an end turned at right angles to the body portion thereof; a standard extending at right angles from the said extending shaft and located midway between the complementary bars; sets of arms secured to the body portion of the complementary bars, rotatably mounted shafts carried by the extended ends of said arms; sets of fingers secured to the shafts; a rocker arm pivotally secured to the standard and connected to the complementary bars; rods extending at right angles from the turned portions of the complementary bars; and a bar connecting the rocker arm with the supporting frame; as and for the purpose specified.

11. In a shocking machine, the combination with a binding machine and its sheaf delivery tray a set of connected beams secured to the binding machine frame, a receiving platform carried by one of said beams and located adjacent the delivery tray and provided with means for delivering the sheaves from the platform, of a main stationary casting secured to the other of the beams and having two parallel arms extending therefrom; a supporting frame pivotally secured between the arms; a cross shaft mounted in the sides of the supporting frame; an extending shaft secured to the cross shaft and passing at right angles therefrom; means for rotating the cross shaft; means for turning the supporting frame and for locking it in such turned position; a pair of complementary bars pivotally secured to the extending shaft and having each an end turned at right angles to the body portion thereof; a standard extending at right angles from the said ex-

tending shaft and located midway between the complementary bars; sets of arms secured to the body portion of the complementary bars rotatably mounted shafts 5 mounted in the ends of said arms; sets of fingers secured to the shafts; a rocker arm pivotally secured to the standard and connected with the complementary bars; rods extending at right angles from the turned 10 portions of the complementary bars; a bar connecting the rocker arm with the supporting frame; a shaft carried by the extending shaft, such shafts being parallel; rods at the end of the latter shaft; cranks at the ends of 15 the shafts carried by the sets of arms links connecting said cranks and rods; and means adapted to rotate the shaft carrying the rods, said fingers and arms being adapted to receive the sheaves passed from the platform to form a shock, as and for the purpose specified.

12. In a shocking machine, the combination with the main beam, of a main casting secured to the beam and provided with arms 25 which extend parallel with the beam; a supporting frame pivotally secured between the arms means for turning the frame a quarter turn; a cross shaft carried by the frame; opposing bevel pinions rotatable on 30 the shaft; a bevel pinion engaging with the aforesaid pinions; means for driving the latter bevel pinion; sets of clutches controlling the operation of the shaft; an extending shaft secured to the cross shaft and fastened at right angles thereto shock forming arms connected with said shaft; a rotatable shaft parallel with and supported from the extending shaft; means adapted 35 to engage with one of the arms of the casting when the frame is turned a quarter turn and throw one of the clutches into engagement thereby rotating the cross shaft; means for disengaging said clutch when the shaft is rotated a quarter turn; means carried 40 by the parallel shaft and adapted to engage with the ground whereby the shaft is rotated in the forward motion of the machine; means carried by the parallel shaft adapted to throw the other of the clutches 45 into engagement and rotate the cross shaft in the opposite or reversed direction; and means whereby the said clutch is thrown out of engagement when the shaft has rotated a 50 quarter turn, as and for the purpose specified.

13. A shocking machine comprising in combination a main and a transverse beam interconnected the one to the other, a carriage wheel, a caster wheel, and a traction 60 wheel supporting the beams, an axle carrying the traction wheel a main casting for the axle secured firmly to the free end of the main beam, the casting being provided with two parallel and extending arms; a 65 drive shaft carried by the upper of the

arms; a bevel pinion and a chain wheel at the opposite ends of the shaft; a corresponding chain wheel secured to the traction wheel a chain connecting said wheels whereby the shaft is rotated; a supporting frame 70 upper and lower pivot pins pivotally securing said frame to the arms means for giving the frame a quarter turn; a cross shaft mounted in the sides of the frame; opposing bevel pinions rotatable on the shaft and carrying the male members of a clutch; a bevel pinion secured to the lower end of the upper pivot pin and engaging with the aforesaid bevel pinions; a bevel pinion secured to the upper end of said pin and meshing with the 80 pinion carried by the drive shaft; female clutch members feathered on the cross shaft; an extending shaft secured to the cross shaft and passing at right angles therefrom shock forming arms connected with said shaft; a 85 rotatable shaft parallel with and supported from the extending shaft; means adapted to engage with one of the arms of the casting when the frame is turned a quarter turn, said means being designed to throw one of the female members of the clutch into engagement thereby rotating the cross shaft; a lug extending from such female clutch member and designed to disengage the members of the clutch when the shaft is rotated 90 a quarter turn; means adapted to rotate the parallel shaft immediately the clutch members are disengaged; and means operated by the rotation of the parallel shaft for throwing the female member of the other of the 95 clutches into engagement whereby the cross shaft is rotated in the opposite or reverse direction; and a lug extending from the female member of said clutch and adapted to disengage the clutch when the shaft is rotated a quarter turn, as and for the purpose specified.

14. In a shocking machine, the combination with a suitably supported stationary main casting having two parallel arms extending therefrom, of a supporting frame pivotally secured to and between the arms, means for giving said frame a quarter turn; a cross shaft mounted in suitable bearings carried by the frame, opposing bevel pinions rotatable on the cross shaft and carrying the male members of a clutch; a bevel pinion intermeshing with the aforesaid pinions and provided with suitable driving means; female clutch members feathered on the shaft and engageable with the male members, said female members having extending portions provided with a peripheral groove; spring bars having their lower ends secured to the frame and their upper ends bifurcated and received within the grooves aforesaid, said bars having each an opening therein: a bar pivotally secured to the frame and adapted to engage with the lower of the arms when the frame is turned a quarter 120 125 130

- the machine and adapted to remain stationary for a short length of time with the deposited shock as the machine progresses and then to return to its original position, 5 as and for the purpose specified.
20. In a shocking machine, the combination with the means designed to deposit a shock on the ground, of means adapted to engage with the ground at a predetermined instant and to remain with the shock when deposited thereby steadyng it; and means for returning the aforesaid means to its normal position, as and for the purpose specified.
- 15 21. In a shocking machine, the combination with the means adapted to deposit the shock on the ground, of coöperating means adapted to engage with the ground when a shock is deposited and to remain stationary 20 with the shock, supporting it, as the machine advances; and means for returning said latter means to its normal position at the end of a predetermined length of time, as and for the purpose specified.
- 25 22. In a shocking machine, the combination with a suitably supported shock forming and depositing means, of a steadier bar having arched strips thereon adapted to partially circumscribe the shock, said 30 steadier bar being supported in such a manner that it engages with the ground and remains stationary with the shock as the machine advances; and means for returning the steadier bar to its normal position, as and for the purpose specified.
- 35 23. In a shocking machine, the combination with the means designed to receive the sheaves and form a shock and adapted to be turned in a horizontal and then in a vertical plane to deliver the shock so formed on the ground, of a steadier bar having arched strips secured thereto and designed to partially circumscribe the shock, said 40 steadier bar being adapted to engage with the ground when the shock is deposited and to remain stationary with the shock as the machine advances; and connections adapted to swing the steadier bar upwardly and away from the shock to its normal position 45 when the shock receiving means is turned in a vertical plane, as and for the purpose specified.
- 50 24. In a shocking machine, the combination with the means designed to receive the sheaves to form a shock and adapted to be turned in a horizontal and then in a vertical plane to deliver the shock so formed on the ground; of a steadier bar designed to turn with the aforesaid means, and to engage with the ground when the shock is 55 deposited thereon and remain in the stationary position with the shock as the machine advances, said steadier bar being returned to its normal position at a pre- 60 determined instant, as and for the purpose specified.
25. In a shocking machine, the combination with a suitably supported shock forming means adapted to be turned horizontally and then vertically to deliver a shock on the ground, of a steadier bar having arched strips secured thereto and adapted to partially circumscribe the shock, said steadier bar being designed to turn with the aforesaid means and to engage with the ground when the shock is deposited and remain stationary with the shock as the machine advances; and means interconnected with the steadier bar whereby said bar is returned to its normal position at a predetermined instant, as and for the purpose specified.
- 70 26. In a shocking machine, the combination with the suitably supported sheaf receiving and shock forming means adapted to be swung horizontally and turned in a vertical plane to deposit the shock on the ground, of a shaft, bearings therefor extending from such supporting means; bars secured to the shaft at their one end, a ring 75 connecting their upper ends; a steadier bar, arched strips secured thereto designed to partially circumscribe the shock, rods connecting said steadier bar with the aforesaid bars the upper end of said steadier bar passing slidably through the ring and the lower end thereof being adapted to engage with the ground when the shock is deposited and to remain stationary with the shock; actuating means and means carried by the shaft 80 and adapted to engage with said actuating means for returning the bar to its normal position at a predetermined instant, as and for the purpose specified.
- 85 27. In a shocking machine, the combination with a stationary suitably supported casting having a pair of parallel arms extending therefrom and a supporting frame pivotally secured to and between the arms, a rotatable cross shaft mounted in the 90 sides of the frame; an extending shaft secured to and passing at right angles from the cross shaft, a parallel shaft carried by the extending shaft; bars firmly secured each to the parallel shaft at their one end, 95 a ring interconnecting their other ends; a steadier bar, rods pivotally securing said bar to aforesaid bars, said steadier bar having its upper end passing slidably through the aforesaid ring; arched strips secured to 100 the steadier bar, said steadier bar being designed to engage with the ground and remain stationary with the shock as the machine advances; actuating means and means carried by the parallel shaft and engageable with said actuating means for returning the steadier bar to its normal position, 105 as and for the purpose specified.
- 110 28. In a shocking machine, the combination with a stationary suitably supported casting having a pair of parallel arms extending therefrom and a supporting frame pivotally secured to and between the arms, a rotatable cross shaft mounted in the 115 sides of the frame; an extending shaft secured to and passing at right angles from the cross shaft, a parallel shaft carried by the extending shaft; bars firmly secured each to the parallel shaft at their one end, a ring interconnecting their other ends; a 120 steadier bar, rods pivotally securing said bar to aforesaid bars, said steadier bar having its upper end passing slidably through the aforesaid ring; arched strips secured to the steadier bar, said steadier bar being designed to engage with the ground and remain stationary with the shock as the machine advances; actuating means and means carried by the parallel shaft and engageable with said actuating means for returning the steadier bar to its normal position, 125 as and for the purpose specified.

28. In a shocking machine, the combination with a stationary suitably supported casting having a pair of parallel arms extending therefrom and a supporting frame pivotally secured to and between the arms, a rotatable cross shaft mounted in the sides of the frame, an extending shaft secured to and passing at right angles from the cross shaft, means for rotating the cross shaft, brackets carried by said extending shaft, a parallel shaft rotatably mounted in said brackets, bars firmly secured to the parallel shaft each at their one end, a ring connecting their other ends; a steadier bar, converging rods pivotally connecting the steadier bar to the aforesaid bars, the upper end of the said steadier bar passing slidably through the ring; arched strips secured to the steadier bar, said steadier bar being designed to engage with the ground when a shock is deposited and remain stationary with the shock as the machine advances; and means for returning the steadier bar to its normal position, as and for the purpose specified.
- 5 29. In a shocking machine, the combination with a stationary suitably supported casting having a pair of parallel arms extending therefrom and a supporting frame pivotally secured to and between the arms, a rotatable cross shaft mounted in the sides of the frame, an extending shaft secured to and passing at right angles from the cross

shaft, and clutch controlled means for operating the cross shaft, of a parallel shaft carried by the extending shaft; bars secured 35 at one end to the parallel shaft, a ring connecting their free ends; a steadier bar passing through the ring; rods pivotally connected to the aforesaid bars and to the steadier bar so that the action of the steadier bar will rotate the said parallel shaft; arched strips secured to the steadier bar; a plate pivotally secured to the supporting frame and for throwing the clutch aforesaid into commission; and an arm extending 40 from the parallel shaft and engaging with the plate to operate the clutch when the parallel shaft is rotated by the action of the steadier bar, as and for the purpose specified.

30. A shocking machine comprising a bar 50 44 extending parallel with the ground, a steadier bar movably supported by said bar, means for forming and depositing a shock from the machine and means holding the steadier bar stationary for a short length 55 of time with the deposited shock as the machine progresses.
